UNITED STATES PATENT OFFICE

WILLIAM F. HUCK, OF BROOKLYN, NEW YORK, ASSIGNOR TO R. HOE & CO., INC., OF NEW YORK, N. Y., A CORPORATION OF NEW YORK

INKING MECHANISM FOR PRINTING PRESSES

Application filed June 30, 1928. Serial No. 289,414.

The present invention relates to inking mechanism for printing presses and particularly for high speed rotary presses, printing on a continuous web of paper.

5 In some ink distributing systems that are regularly employed, the ink is taken from a reservoir which may be what is commonly known as an ink fountain, in which case the ink is transferred from a roller within the fountain to an ink distributing cylinder by means of a ductor roller, which is caused to make contact alternately with the fountain roller from which it receives ink, and then with the ink distributing cylinder on which it 10 deposits the ink it previously received.

Other ink distributing systems comprise a plurality of pumps which draw ink from a reservoir and force it through suitable conduits to and through an ink rail having orifices adjacent the periphery of the ink distributing cylinder. An ink supply device with which pumps are employed is used herein to illustrate the invention but it will be understood that the invention is also applicable to 20 presses on which other ink supply devices are used.

After the ink is deposited on the ink distributing cylinder it is usually distributed evenly over the surface of the cylinder by 30 smaller diameter rollers covered with a suitable composition and running in surface contact with the cylinder. These rollers are caused to vibrate or move back and forth endwise in timed relation to the revolution of 35 the cylinder, in order to properly distribute the ink. They must be held against the cylinder with considerable pressure and when the bearings are properly adjusted to produce the proper pressure at the ends of the rollers 40 it has been found that owing to the small diameter of the rollers they are caused to bend and there is little or no pressure against the cylinder at a point midway of their length.

The bending action of the rollers cramps 45 the shafts in the bearings and is a factor that causes excessive wear of the roller sockets. Wear of these roller sockets on inking mechanisms as heretofore made is also caused by the excessive pressure on one side of the 50 bearings due to the fact that but one side of

each ink roller is in contact with a cylinder.

The invention herein disclosed provides an arrangement of distributing cylinders and ink rollers that obviates the difficulties mentioned and constitutes an ink distributing system giving the desired results though employing a minimum number of moving parts. 55

An object of the invention is to provide an ink distributing system comprising ink distributing cylinders and ink rollers in which the rollers are supported so there is no tendency to bend them axially and pressure on their bearings is minimized. 60

Another object of the invention is to provide an efficient ink distributing system having a minimum number of moving parts. 65

Still another object of the invention is to provide an ink distributing system that is of generally improved construction, simple, durable, inexpensive in construction, and practical, serviceable and efficient in its use. 70

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention. 75

In the accompanying drawings which show preferred embodiments of the invention,

Figure 1 is a side elevation partly in section and partly broken away showing a portion of a rotary web printing press with one form of the improved inking mechanism, as viewed on the line 1-1 of Figure 2. 85

Figure 2 is a fragmentary view showing an elevation taken at right angles to Figure 1 and illustrating a portion of the inking mechanism as viewed in the direction of arrow 2 of Figure 1; and 90

Figure 3 is a fragmentary view of a modified form of the invention being in other respects similar to Figure 1. 95

Referring to the drawings, 11 indicates a side frame of a printing press in which an impression cylinder 12 and a form or plate cylinder 13 is supported in suitable bearings 100

so they may print on a web or sheet 14 as it passes between them. Two similar side frames are used, one on each side of the press, and various elements of an inking system for supplying ink to the plate cylinder are supported by the frames and will be hereinafter described.

Halliwell Patent No. 1,644,723 dated October 11, 1927, shows an ink pump with 10 conduits connecting it to an ink distributing rail mounted adjacent to an ink distributing cylinder. The form of ink pump shown in the Halliwell patent is indicated in dotted lines at 15 and the ink rail at 16, the latter having 15 a series of orifices arranged crosswise of the press one of them being shown at 17.

A primary ink distributing cylinder 18 is supported in suitable bearings with its surface adjacent to the orifices in the ink rail 20 and receives ink therefrom.

Intermediate ink cylinders 19 and 20 are supported in adjustable bearing blocks 21 and 22 and ink rollers 23 and 24 having a suitable composition covering are journaled 25 in arms 25 and 26 so as to be in running contact with both the primary ink distributing cylinder and also the intermediate ink cylinder. Similarly ink rollers 27 and 28 are journaled in arms 29 and 30 and are held in 30 running contact with the intermediate ink cylinders and a secondary ink distributing cylinder 31.

The form rollers 32 and 33 are suitably supported in bearings which are omitted from 35 the drawing for clearness, and are held in running contact with the secondary ink distributing cylinder and the printing plates carried on the plate cylinder.

The distributing cylinders are driven from 40 any suitable source of power and are connected together by the usual gearing so they rotate at the same speed. In the preferred construction, a gear 34 is secured to the plate cylinder 13 and meshes with an idler 35. 45 This idler meshes with a gear 36 that is fastened to the shaft carrying the secondary ink distributing cylinder 31. Gear 36 in turn meshes with another idler 37 that meshes with a gear 38 fastened to the shaft carrying the 50 primary ink distributing cylinder 18. The ratio of the gearing may be such that the cylinders are all driven at the same peripheral speed, or if desired, it may be proportioned to drive them at different speeds. As the ink 55 rollers are held in contact with the cylinders they will of course be driven by friction.

From the above it will be understood that ink ejected from the orifices 17 in the ink rail, will be deposited on the primary ink 60 distributing cylinder 18 from which a portion of it will be taken off by the ink roller 24 and deposited on the intermediate ink cylinder 20. From there it will pass on to the ink roller 28 and then to the secondary 65 ink distributing cylinder 31.

Another portion of the ink deposited on the ink cylinder 18 will be taken off by the ink roller 23 and deposited on the intermediate ink cylinder 19. From there it will pass on to the ink roller 27 and then to the 70 secondary ink distributing cylinder 31.

From the cylinder 31 the ink passes to the form rollers 32 and 33 which deposit it on the printing plates.

In order that the ink may be properly distributed it is customary to give an endwise or vibrating motion to certain of the ink rollers and ink cylinders. In the construction heretofore used a considerable number of the rollers have been vibrated and as they 80 are mounted around the periphery of the ink distributing cylinder, it requires very complicated mechanism to impart the required vibratory motion to them. In the inking system herein disclosed, none of the 85 ink rollers are vibrated and a very simple lever mechanism serves to vibrate the two ink distributing cylinders.

The shafts of the cylinders 18 and 31 have grooved collars 39 and 40 fastened to them, 90 which are engaged by rollers 41 and 42 that run in the grooves. These rollers are rotatably mounted on opposed arms 43 and 44 of a three armed lever pivoted in the bracket 45 which is secured to the frame 11. The third arm 46 of the lever projects forward from the bracket and is pivotally connected to the rod 47 which is given a reciprocating motion by any suitable mechanism driven from the press or from a separate source of 100 power.

The arms 25, 26, 29 and 30 which support the ink rollers have slotted ends that engage with suitable pins 48 secured to the frame 11, and their opposite ends which are also 105 slotted engage with the shaft of the rollers 19 and 20.

The bearing blocks 21 and 22 are fitted to slide between suitable guide ways 49 and 50; and screws 51 having handwheels 52 and collars 53, pass through clearance holes in the blocks 21 and 22 and are threaded into the main frame 11, thus providing means for adjusting the position of the intermediate ink cylinders 19 and 20. It will be understood that by moving the ink cylinders 19 and 20 toward each other the ink rollers 23, 24, 27 and 28 will be pressed between the ink cylinders 19 and 20 and the ink distributing cylinders 18 and 31. It is thus possible to 115 adjust this pressure to a nicety and as the pressure on both sides of the ink rollers is equalized springing is avoided and contact is obtained over the entire length of the cylinders, thus insuring proper distribution of 120 the ink.

In order to facilitate removal of the ink rollers, their bearings are provided with hinged caps 54 secured by lock nuts 55.

In the modified form of the invention 125

shown in Figure 2, the bearings for the ink rollers 23 and 27 are carried in arms 56 and 57 pivoted respectively on studs 58 and 59 secured to the frame 11. It will be understood that similar arms are provided to support ink rollers corresponding to those indicated at 24 and 28 in Figure 1, and that duplicate arms are provided to support the shafts on the other ends of the rollers. With 10 this arrangement the ink rollers are supported between the ink cylinders so as to avoid axial bending strains and adjustment of contact pressure is effected in the same manner as in the construction shown in 15 Figure 1.

It will be seen that the constructions illustrated and described constitute an ink distributing system that insures a proper distribution of ink over the entire surface of 20 the printing plates, and that only simple mechanism is employed having but few moving parts.

What I claim is:

1. In an ink distributing system for a printing press, ink cylinders having fixed bearings, ink cylinders having adjustably mounted bearings, and ink rollers held in alignment between certain of the ink cylinders and having movable supports.
2. In an ink distributing system for a printing press, a primary ink distributing cylinder, an ink roller in operating engagement therewith, an intermediate ink cylinder in operating engagement with the ink roller, a second ink roller in operating engagement with the intermediate ink cylinder, and a secondary ink distributing cylinder in engagement with the second ink roller, said cylinders and said rollers being so located with respect to each other that adjustment of the intermediate ink cylinder varies the pressure between the cylinders and the rollers.
3. In an ink distributing system for a printing press, a primary ink distributing cylinder, an ink roller in operating engagement therewith, an intermediate ink cylinder in operating engagement with the ink roller, a second ink roller in operating engagement with the intermediate ink cylinder, and a secondary ink distributing cylinder in engagement with the second ink roller, said cylinders and said rollers being so located with respect to each other that the cylinders contact along approximately opposite sides of said rollers.

4. In an ink distributing system for a printing press, an ink cylinder having fixed bearings, a second ink cylinder having adjustably mounted bearings, an ink roller rotatably supported in yieldable bearings and between the first and second ink cylinders, and means for adjusting the adjustably mounted bearings.

5. In an ink distributing system for a printing press, first and second ink distrib-

uting cylinders having fixed bearings, a third ink distributing cylinder having adjustably mounted bearings, a first ink roller supported on yieldable bearings between the first and third cylinders, a second ink roller supported on yieldable bearings between the second and third cylinders, and means for adjusting the bearings for the third cylinder, and thereby adjusting the pressure exerted on the ink rollers.

6. In an ink distributing system for a printing press, a primary ink distributing cylinder, an intermediate ink cylinder, a secondary ink distributing cylinder, an ink roller supported on yieldable bearings between the primary ink cylinder and the intermediate cylinder, another ink roller supported on yieldable bearings between the intermediate cylinder and the secondary ink cylinder, and means for adjusting the bearings of the intermediate cylinder and thereby adjusting the pressure exerted on the ink rollers.

7. In an ink distributing system for a printing press, a primary ink distributing cylinder supported in fixed bearings, an intermediate ink cylinder supported in adjustably mounted bearings, a secondary ink distributing cylinder supported in fixed bearings, ink rollers on yieldably supported bearings, between the primary cylinder and the intermediate cylinder, ink rollers on yieldably supported bearings, between the intermediate cylinder and the secondary cylinder, and means for adjusting the bearings of the intermediate cylinder and thereby adjusting the pressure on the ink rollers.

8. In an ink distributing system for a printing press, a primary ink distributing cylinder, ink rollers in operating engagement therewith, intermediate ink cylinders in operating engagement with the said ink rollers and each having its axis in a plane substantially common to the axis of the primary ink cylinder and the axis of one of the ink rollers, other ink rollers in operating engagement with the intermediate cylinder, a secondary ink distributing cylinder in operating engagement with said other ink rollers and having its axis at the intersection of planes, one of which is substantially common to the axis of one of said other rollers and the axis of one of the intermediate cylinders, and the other of which is substantially common to the axis of the other of said other rollers and the axis of the other intermediate cylinder, and means for adjusting the bearings of certain of the cylinders, and thereby adjusting the pressure on the rollers.

9. In an ink distributing system for a printing press, a primary ink distributing cylinder supported in fixed bearings, a secondary ink distributing cylinder supported in fixed bearings and spaced apart from the primary cylinder, an intermediate cylinder supported in adjustably mounted bearings

with its axis parallel to the axes of the ink distributing cylinders but relatively distant from the plane common to the axes of the primary and secondary cylinders, ink rollers operatively interposed between the primary cylinder and the intermediate cylinder, and between the intermediate cylinder and the secondary cylinder, and means for adjusting the bearings of the intermediate cylinder to regulate the pressure on the rollers.

10. In an ink distributing system for a printing press, a primary ink distributing cylinder supported in fixed bearings, a secondary ink distributing cylinder supported in fixed bearings and spaced apart from the primary cylinder, intermediate ink cylinders supported in adjustably mounted bearings, each having its axis parallel to the axes of the ink distributing cylinders, but relatively distant from, and on opposite sides of the plane common to the axes of the primary cylinder and secondary cylinder, ink rollers operatively interposed between the primary cylinder and the intermediate cylinders and between the intermediate cylinders and the secondary cylinder, and means for adjusting the bearings of the intermediate cylinders to regulate the pressure on the rollers.

In testimony whereof, I affix my signature.
